ACCOUNTING MACHINE

Walter J. Kreider, Dayton, Ohio, assignor to The
National Cash Register Company, Dayton,
Ohio, a corporation of Maryland

Application July 26, 1943, Serial No. 496,122

2 Claims. (Cl. 271—71)

This invention relates to cash registers and accounting machines, and particularly to slip, bill, statement or card ejecting mechanism adapted to be used in machines of the type illustrated and described in United States Letters Patent No. 1,916,535, issued July 4, 1932, to Bernis M. Shipley, and No. 2,141,332, issued December 27, 1938, to Charles H. Arnold, and is an improvement over the ejecting mechanism in the patent to John Earl Gates, No. Re. 21,442, dated May 7, 1940.

It is a common practice among public utility companies, such as telephone companies, electric and gas companies, and water companies, to furnish their customers periodically with statements of their accounts. Such statements before being mailed out to the customers are usually composed of a plurality of detachable portions, namely, an office copy, a customer's statement, and a cashier's stub. Each of the different portions of the statement bears the same information identifying that particular account and the amount due for the service rendered to the customer.

Such statements or bills are of varying widths and also of varying thicknesses. In some cases the material used is of a paper substantially the same thickness as a standard Government postal card, and again in other instances the statements may be on very flimsy paper, which is inserted in envelopes and mailed to the customers. In the heavier type of paper the statement itself is mailed as a postal card.

In making up the bills or statements the operator inserts the form into the machine against a stop, after which the machine, by means of a feeding mechanism, draws the form into the machine in position to be printed upon either once or a plurality of times, depending upon the type of bill or statement which is to be issued to the customer. After the last printing has taken place, which is usually the total of the bill, the statement is fed forwardly into a position to be ejected from the machine.

It is with this ejecting mechanism that the present invention is particularly involved. In some of the machines on the market the bills or statements are fed a considerable distance and then a gripping device grips the bill or statement and ejects it from the machine, and at the same time inverts the bills so they will be in their proper sequential or alphabetical order, depending on how the operator has them arranged in the first place. Sometimes, due to the very thinness of

the paper used, and also, even due to the fact that the paper is of a very heavy texture, the ejection mechanism occasionally will crumble or bend the statements, and sometimes they may even catch in the machine and not be completely ejected.

To avoid such things happening the present invention is arranged to grip the bill or statement at or near the leading edge thereof and eject it from the machine, and at the same time invert it so as not to destroy the sequential or alphabetical order of the stack.

By gripping the statement or bill near the leading edge thereof, such statement or bill is not pushed, but is drawn out of the machine and at the same time automatically inverted without in any way placing any strain on the paper.

It is therefore an object of this invention to provide a novel combination of elements to eject and invert a statement or bill from the machine after it has been printed upon, regardless of the thinness or the thickness of the material used for the bill.

Another object of this invention is to provide a novel ejecting and inverting mechanism for inserted statements or bills to grip the statement by the leading edge thereof after it has been fed to a designated position, and then eject said bill or statement by drawing it completely out of the machine, thus eliminating all friction which attends ejecting mechanisms where the paper or statement is pushed out through a chute, thus definitely eliminating all strains and stresses on the paper and preventing crumpling, creasing or buckling thereof.

With these and incidental objects in view the invention includes certain novel features of construction and combinations of parts, the essential elements of which are set forth in appended claims, and a preferred form or embodiment of which is hereinafter described with reference to the drawing which accompanies and forms a part of this specification.

Of said drawing:

Fig. 1 is a view showing a portion of the ejecting mechanism and its relation to the type wheels and the feeding mechanism for the bill or statement sheet, the ejecting mechanism being in normal position, with the gripping finger open.

Fig. 2 is a detail view of a portion of the ejecting mechanism, in a moved position, and shows the finger closed, and in a position just before the finger is opened to receive the statement sheet as it is being fed from the machine after the final printing has taken place.

Fig. 3 is a plan view, partly broken away, showing a pair of ejecting devices in their normal positions, and also shows in dot and dash lines a driving means for the ejecting means.

Fig. 4 is a detail view of a portion of the ejecting means shown in the position just after the finger has been opened to receive the statement sheet as it is fed from the printing mechanism.

Fig. 5 is a detail view of a portion of the ejecting mechanism shown in the position that it assumes just prior to the time it releases the statement sheet or bill.

Fig. 6 is an enlarged detail view of a portion of the gripping finger, showing the serrations on the inside thereof, which cooperate with the bill or statement sheet.

General description

Described in general terms, the present invention in the specific embodiment shown, comprises a pair of ejecting devices mounted on a shaft to be operated in synchronism by a rack and pinion driving mechanism.

Each of the ejecting devices includes a flanged segment or plate carrying a pivoted gripping finger which is adapted to be opened and closed relatively to the flange of the segment to grip the paper or statement sheet to eject and invert the same and to release the statement after it has been ejected and inverted.

The invention herein is shown as having been applied to a machine of the type shown in the above mentioned Arnold Patent, No. 2,141,332. Therefore, only a small portion of the mechanism of that patent is shown herein in Fig. 1. This mechanism includes a part of the statement sheet feeding mechanism, a type wheel, and one of the hammers.

Detailed description

As has been previously stated, a small portion of the printing and feeding mechanism of the type shown and described in the above mentioned Arnold Patent No. 2,141,332, has been shown herein, in order to show the relationship between such printing and feeding mechanisms and the novel ejecting mechanism of the present application.

The greater part of the printing mechanism is supported between side frames 61 and 62 (Figs. 1 and 3) which are secured to a base (not shown), and which are connected by several tie bars 63 (only one being shown).

Statement sheet or slip feed rollers 64 (only one being shown) are secured to a shaft 65 which is supported by the frames 61 and 62. The feed rollers 64 are driven through the rotation of the shaft 65 by means fully illustrated and described in the above mentioned Arnold and Gates patents. The feeding rollers 64 are notched to provide stopping shoulders 66 to form locating positions for a statement sheet or slip 70 when it is first inserted into the machine by the operator.

Pressure rollers 71 (only one being shown) cooperate with the feed rollers 64 to feed the statement sheet 70 into the machine, into position to be printed upon and also to line space the sheet when it is necessary to do so, according to the number of prints to be made thereon. The printing is accomplished by type wheels 72 and hammers 73. The hammers 73 are pivoted on a rod 74 supported by the frames 61 and 62.

A table 75 is supported on top of the frames 61 and 62, and has guides 76 to guide the statement sheet 70 in its initial insertion into the machine

against the shoulder 66. A plate 77, also supported by the frames 61 and 62, supports the statement sheet 70 upon its insertion into the machine.

5 A pivoted deflector 78 is also used to guide the statement sheet 70 when it is being inserted into the machine. This deflector 78 is shown in its normal position in Fig. 1, and in Figs. 2, 4 and 5 it is shown in the position it assumes after the printing has taken place and before the statement sheet 70 has been fed outwardly by the rollers 64.

10 The operation of the above parts is as follows: The operator inserts a statement sheet between the guides 76, underneath the deflector 78 and against the shoulders 66 into the position as shown in Fig. 1. After this insertion the feed rollers 64 are rotated clockwise to feed the statement sheet 70 into the machine, into position to be printed upon by the type 72. Other step-by-step feeds may or may not take place, depending upon whether or not there is to be one or a multiplicity of prints upon the statement sheet 70. After the printing has taken place, the rollers 64 feed the statement sheet 70 toward the left (Fig. 1). Prior to this feeding of the sheet 70 the deflector 78 is moved from the position shown in Fig. 1 to the positions shown in Figs. 2, 4 and 5, whereupon the deflector 78 deflects the leading 15 edge of the statement sheet 70 downwardly into the position shown in Fig. 4, where it is ready to be ejected from the machine by the ejecting mechanism.

Ejecting and inverting mechanism

20 The ejecting mechanism includes a shaft 80 mounted in the frames 61 and 62 and having secured thereto a pair of segments 81, each having a flange 82, as is clearly shown in Figs. 1 to 5.

25 The shaft 80 is rotated first clockwise and then counter-clockwise, for a purpose to be herein-after described, by means of a pinion 83 secured to the end thereof, which is driven by a rack 84. This rack 84 is driven to the left by any of the usual forms of camming devices (not shown), and is returned to the right to its normal position by a spring 85. The object of the spring return is to give the ejecting mechanism a faster rotation in a counter-clockwise direction to eject and invert the statement sheet 70. Adjacent each of the segments 81 is a bracket 90. These brackets are secured to the tie bar 63, and the outer ends of the brackets 90 partially surround the shaft 80. Each bracket 90 has secured thereto a cam plate 91 and a stud 92, the purpose of 30 which will be hereinafter described.

35 Pivoted at 93 to an arm 94 on each of the segments 81 is an ejecting arm 95 having an integral gripping finger 96 adapted to cooperate 40 with the flange 82 so as to grip the statement sheet 70 just prior to the time it is to be ejected. In order to provide a better grip for the finger 96 on the statement sheet, the underside of the end of the finger 96 is provided with a plurality of serrations 97 shown only in the enlarged view 45 in Fig. 6.

50 A spring 98 stretched between a stud on the ejecting arm 95 and a stud on the segment 81 normally holds a pin 99 (Fig. 1) against the outer surface of the cam plate 91 so as to hold the finger 96 away from the flange 82, or in other words, in the open position, as shown in Fig. 1. This is the normal position of the finger 96 relative to the flange 82. The spring 98 tends to 55

rock the ejecting arm 95 clockwise at all times around its pivot 93.

The operation of the ejecting and inverting mechanism is as follows.

In Fig. 1 the parts are all shown in their normal positions, and the statement sheet 70 is shown as having been inserted in the machine against the shoulder 66 of the feeding roller 64.

As has been previously stated, the statement sheet 70 is fed into the machine to the printing line and printed upon by the type wheels 72 through the action of the hammer 73. There may be one print made on the statement sheet or there may be several prints made thereon, depending upon the system and the information desired to have placed on the statement sheets before they are mailed out. However, after the final printing, which as above stated is usually the total, the statement sheet is fed into the position shown in Fig. 4.

Prior to this feeding of the statement sheet 70 into the position in Fig. 4, the rack 84 is moved to the left as viewed in Fig. 1, thus rotating the shaft 80 in a clockwise direction, and since the segments 81 are secured to the shaft, these segments receive such clockwise movement. When the segments 81 reach the position shown in Fig. 2, it will be noticed that a beveled or camming surface 100 of the ejecting arm 95 has just contacted the stud 92, which is secured to the stationary bracket 90. Upon further clockwise movement of the segment 81, the stud 92, through the camming surface 100, forces the ejecting arm 95 to be rocked in a counter-clockwise direction against the influence of the spring 98 until the surface 100 is just above the stud 92, as shown in Fig. 4, in which position the gripping finger 96 has become fully opened, that is, it has been separated from the flange 82. The segment 81 is maintained in the position shown in Fig. 4, with the gripping finger 96 opened until all of the printing has taken place, and until the statement sheet 70 has been fed into the position shown in Fig. 4, wherein the leading end thereof has passed between the gripping finger 96 and the flange 82.

With the parts in the positions shown in Fig. 4, the rack 84 has been moved to its extreme lefthand position, and is now in a position to be released by its driving mechanism, whereupon the spring 85 rapidly moves the rack 84 back to the right, into the position shown in Fig. 1, whereupon the shaft 80 and segments 81 are moved very rapidly in a counter-clockwise direction from the position shown in Fig. 4.

During such counter-clockwise movement of the segment 81, the surface 100 is moved downwardly and away from the stud 92 in the bracket 90. Under the action of the spring 98 the arm 95 at the same time is rocked in a clockwise direction around its pivot 93, thus causing the gripping finger 96 to close itself against the flange 82, thus firmly gripping the leading edge of the statement sheet 70 between the flange 82 and the finger 96 to eject and invert the same.

When the segment 81 reaches the position shown in Fig. 5, the pin 99 on the ejecting arm 95 just contacts the outer edge of the camming plate 91, and the continued counter-clockwise movement of the segment 81 causes this stationary camming plate 91 through the pin 99 to rock the ejecting arm 95 counter-clockwise around its pivot 93 to move the gripping finger 96 away from the flange 82, thus releasing the statement sheet 70.

Now should the statement sheet 70 adhere to the serrations 97, the leading edge of the statement sheet will contact the under edges 101 of the brackets 90, and as the segment 81 continues in its counter-clockwise movement from the position shown in Fig. 5 to that shown in Fig. 1, which is the normal position, the statement sheet 70, assuming that it adheres to the serrations 97, will be stripped by striking the under edges 101 of the brackets 90. It can be seen, therefore, that the statement sheet has been not only very rapidly ejected and in a positive fashion from the machine, but it has also been inverted and deposited in a receptacle 102 (Fig. 1) which is secured to the tie bar 63.

From the above description it can be seen that when the segment 81 is moved in a clockwise direction from its normal position shown in Fig. 1 as the pin 99 on the ejecting arm 95 leaves the camming plate 91, the spring 98 will rock the ejecting arm 95 in a clockwise direction around its pivot 93 and cause the gripping finger 96 to contact the flange 82; but, as the beveled surface 100 of the ejecting arm 95 contacts the stud 92 when it reaches the position shown in Fig. 2, the arm 95 is rocked counter-clockwise on its pivot 93 to open the gripping finger 96, that is, move it away from the flange 82 into the position shown in Fig. 4, as the segment 81 completes its clockwise movement, after which the statement sheet 70 is fed into the position shown in Fig. 4. When the rack 84 is released, the spring 85 very rapidly returns the rack 84 to the right to its normal position, whereupon the segment 81 is rotated counter-clockwise to its normal position. At the very beginning of this movement the arm 95 is moved away from the stud 92 and the spring 98 closes the finger 96 to grip the statement sheet 70 and thus draw or eject the statement sheet from between the deflector 78 and table 77, invert said statement sheet, and release it from the ejecting device when the stud 99 rides upon the camming plate 91 as the segment 81 is moved counter-clockwise into its final or normal position.

While the form of mechanism herein shown and described is admirably adapted to fulfill the objects primarily stated, it is to be understood that it is not intended to confine the invention to the form or embodiment herein disclosed, for it is susceptible of embodiment in various forms, all coming within the scope of the claims which follow:

What is claimed is:

1. In a device for ejecting and inverting record material, in combination with an oscillating means, a gripper finger pivotally mounted on said oscillating means, and a spring to force said finger against the oscillating means to grip record material to feed the record material when the means is oscillated, of a single element mounted adjacent the gripping finger, said single element having a cam for camming the finger away from the oscillating means preparatory to receiving record material, said element having a second cam for camming the finger away from the oscillating means to release the record material at a certain location, said element having a stripping means to positively strip the record material from the oscillating means after the finger is cammed by said second cam at said certain location.

2. In a device for ejecting and inverting record material, in combination with an oscillating means, a gripper finger pivotally mounted on

said oscillating means, and a spring to force said finger against the oscillating means to grip record material to feed the record material when the means is oscillated, of a stationary bracket having a cam projecting into the path of movement of the finger to withdraw the finger from against the oscillating means preparatory to receiving record material, said stationary bracket having a second cam projecting into the path

of movement of the finger when the oscillating means has fed the record material a fixed extent, said stationary bracket having a surface against which the leading edge of the record material is moved when fed said fixed extent whereby the record material is positively arrested and stripped from the oscillating means.

WALTER J. KREIDER.
